PANEL OR THE LIKE

Martin R. Dohren, 211 Rockland Ave.,
Staten Island, N.Y. 10306

Filed Sept. 21, 1966, Ser. No. 3,946

Term of patent 14 years

(Cl. D13—1)

FIG. 1

FIG. 4

FIG. 2

FIG. 3

FIG. 1 is a front elevational view of a panel embodying my new design;

FIG. 2 is a top plan view thereof, the bottom thereof being identical;

FIG. 3 is an enlarged sectional detail view taken along the line 3—3 in FIG. 1; and

FIG. 4 is a side elevational view thereof, the other side being identical.

The rear of the panel not shown is plain and unornamented.

I claim:

The ornamental design for a panel or the like, as shown and described.
